DESIGN FOR A SEPARABLE FUR SCARF

Jack Zimmerman, New York, N. Y.

Application February 22, 1943, Serial No. 109,600

Term of patent 3½ years

To all whom it may concern:

Be it known that I, Jack Zimmerman, a citizen of the United States, residing in New York city, in the county of New York and State of New York, have invented a new, original, and ornamental Design for a Separable Fur Scarf, of which the following is a specification, reference being had to the accompanying drawing, forming part thereof.

Fig. 1 is an elevational front view of a separable fur scarf showing my design.

Fig. 2 is a front view of one section of the scarf shown in Fig. 1, and

Fig. 3 is a view of the reverse side of Fig. 2.

I claim:

The ornamental design for a separable fur scarf, substantially as shown.

JACK ZIMMERMAN.
